(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outer dot-dashed broken lines in the FIGURE show a display screen or portion thereof, and form no part of the claimed design. The other dot-dashed broken lines in the FIGURE show portions of the graphical user interface that form no part of the claimed design.
